Wm. Wharton Jr.

United States Patent Office.

WILLIAM WHARTON, JR., OF PHILADELPHIA, PENNSYLVANIA.

Letters Patent No. 78,165, dated May 19, 1868.

IMPROVED RAILROAD-SWITCH.

The Schedule referred to in these Letters Patent and making part of the same.

TO ALL WHOM IT MAY CONCERN:

Be it known that I, WILLIAM WHARTON, Jr., of Philadelphia, Pennsylvania, have invented an Improvement in Railroad-Switches; and I do hereby declare the following to be a full, clear, and exact description of the same.

My invention relates to a modification of that described in the Letters Patent granted to me on the 27th day of June, A. D. 1865, and consists of a permanent rail and laterally-flexible rail of a main track, in combination with a movable switch-rail, forming a continuation of one of the rails of a turnout, and the fixed rail of the same, operating in the manner and for the purpose described hereafter.

In order to enable others skilled in the art to make and apply my invention, I will now proceed to describe its construction and operation, reference being had to the accompanying drawing, which forms a part of this specification, and in which—

Figures 1 and 2 are plan views of my improved railroad-switch, and

Figure 3 a sectional perspective view on the line 1-2, fig. 2.

A and A' are the rails of the main track, and B and B' those of the siding or turnout.

The rail B, from about the point x to its outer end, is unconfined laterally to the track, and thus becomes, between these points, a switch-rail, D, admitting of being moved to the position shown in fig. 1, away from the main rail A, or to that seen in fig. 2, where it is in contact with the outer side of the said rail.

The upper surface or tread of this switch-rail D, is at its extreme outer end, on a level with the tread of the main rail, but is gradually inclined upwards, as described in my said patent, and as seen in fig. 3.

In the present instance, this switch-rail D is operated by a horizontal lever, E, to which the rail is connected by a link, F; the said lever turning on a pin secured at a suitable point adjacent to the track, and its outer end being connected by a rod, G, to the rail A' of the main track; this rail being so secured to the sleepers that it can be bent from the position shown in fig. 1 to that seen in fig. 2. When thus bent, the rail A is in contact with the straight outer edge of the pointed termination of the rail B', to receive which, the side of the rail A' may be cut away to the limited extent shown in the drawing.

As seen in fig. 1, the switch-rail D has been moved away from the rail A, and the rail A' from the side of the termination of the rail B'; hence the rails of the main track are free for the travel over them of the cars in either direction.

On operating the lever E, however, so that the switch-rail D is brought into contact with the rail A, simultaneously with the bending of the rail A', until it is in contact with the rail B', cars moving over the track in the direction of the arrow will pass from the main track to the turnout, or, in the contrary direction, from the turnout to the main track.

If, for instance, a car be moving in the direction of the arrow, fig. 2, the wheels traversing the rail A will gradually mount the inclination at the end of the switch-rail D, and be brought under the control of the rail B of the turnout, the wheels having been so far elevated that their flanges will cross the main rail, at the same time the wheels at the opposite side of the car will follow the bent rail A', and pass from the control of the same to that of the rail B' of the turnout.

I claim as my invention, and desire to secure by Letters Patent—

The permanent rail A, and laterally-flexible rail A' of the main track, in combination with the movable switch-rail D, forming a continuation of the rail B of the turnout, and the fixed rail B' of the same, the whole being arranged and operating substantially as and for the purpose herein set forth.

In testimony whereof, I have signed my name to this specification in the presence of two subscribing witnesses.

Witnesses:

JOHN WHITE,
HARRY SMITH.

WM. WHARTON, JR.
